UNITED STATES PATENT OFFICE.

JAMES B. POPE, OF SAN FRANCISCO, CALIFORNIA.

DIFFERENTIAL AXLE FOR RAILROAD CARS.

Application filed August 9, 1926. Serial No. 128,127.

This invention relates to railway rolling stock and particularly pertains to differential axles for railway cars.

It is common practice in the operation and maintenance of railway cars to provide car axles having a flanged track wheel rigidly secured at each end of the axle. Such a construction, however, contributes to the rapid wearing of the rails, journals, trucks and wheels of the cars, as well as often produces broken wheels and broken or sprung axles.

Another marked detriment caused by the use of a rigid axle to which the wheels are fixed is that due to variable friction upon the two rails of the track and excessive resistance offered when the wheels of an axle are travelling on a curved track, a considerable amount of the driving force of the engine is dissipated, this being caused by the necessity for slippage between the wheels and the rails as they are forced to travel along different lineal distances while rotating in unison.

It is the principal object of the present invention, therefore, to provide means for permitting differential operation of the two wheels carried by a railroad axle so that the two wheels of each axle will readily adapt themselves to varying road conditions, slip-page and friction coefficients, thereby decreasing shock upon all of the parts in preventing wear of the rails and wheels.

The present invention contemplates the use of an axle formed in two longitudinally aligned sections, the outer ends of each section being fitted with a wheel and the contiguous ends of the sections being held together in a manner to prevent relative longitudinal movement while permitting independent rotation.

The invention is illustrated by way of example in the accompanying drawing, in which—

Fig. 1 is a view in section and elevation showing the truck of a railway car and more particularly disclosing the differential axle.

Fig. 2 is an enlarged view in perspective showing one-half of the differential coupling sleeve and further indicating a part of one axle section in solid lines and another part of said section in dotted lines.

Fig. 3 is an enlarged transverse section through the differential axle as seen on the line 3—3 of Figure 1.

Fig. 4 is an enlarged view in perspective

showing one of the differential sleeve pins.

Referring more particularly to the drawing: 10 indicates a railway car mounted upon suitable girders 11, which are in turn carried by the cross beams 12. These beams are designed to rest upon suitable spring suspension members 13, carried by truck frames 14. Journal boxes 15 also form a part of the truck frames 14 and are adapted to receive the outer projecting ends of an axle 16. This axle carries flanged rail wheels 17 and 18. In the present instance, the rail wheels are independent of each other, due to the fact that the axle 16 is formed in sections 19 and 20, upon which the wheels 17 and 18 are mounted respectively. The sections 19 and 20 of the axle 16 are held in longitudinal alignment and are permitted to have independent rotation around their longitudinal axis due to the provision of a differential coupling sleeve 21. This sleeve is formed in two semi-circular halves 22 and 23, as more clearly shown in Fig. 3 of the drawing. Complementary interlocking lugs 24 are formed upon diametrically opposite sides of the sleeve sections 22 and 23, and extend above and below the parting line of the sleeves. By reference to Figure 2 of the drawing, it will be seen that these lugs are uniformly spaced with relation to each other along the opposite sides of the sleeve members.

By reference to Figure 1, it will be seen that the lugs of one-half of the sleeve are staggered with relation to the other half of the sleeve so that they become complementary and interlock. This makes it possible to securely fasten the two halves of the differential coupling sleeve together by two pins 25, which extend parallel to the longitudinal axis of the sleeve and project through a gradually tapering opening formed through the series of interlocked lugs 24 along opposite sides of the sleeve. By driving the tapered pins through the openings 26, it is possible to firmly hold the two halves of the differential coupling sleeve together without causing the halves to variably and objectionably grip the axle sections 19 and 20 when the sleeve is in position thereon. Cotter pins 27 are provided to be driven through the smaller ends of the pins to prevent the sleeve pins from accidentally loosening and working their way out of the sleeve. The assembled differential coupling sleeve 21 is formed with a

longitudinally extending central bore 28, which substantially agrees with the outside diameter of the axle sections 19 and 20. Formed at equal spaced intervals along the face of the bore 28 are shoulders 29 which have a circular face described by a circle of smaller diameter than the diameter of the axle, but concentric thereto. The shoulders thus spaced provide intermediate 5 grooves 30 of substantially the same width as the shoulders. It will also be noted, by reference to Figure 2, that the lugs 24 for the most part occur opposite the groove section and act to reinforce the same, while the shoulders occur in the relatively weaker 10 points between the lugs and act to reinforce the wall of the differential sleeve. By this design and arrangement it is possible to secure a strong coupling sleeve for the purpose intended but by the use of a minimum amount of metal.

The cylindrical face of the contiguous 25 ends of the axle sections 19 and 20 are formed with grooves 31 of a width and depth to properly receive the shoulders 29 of the coupling sleeve when the shoulders are fitted therein and the halves of the coupling sleeve are secured together by the pins 25. This means makes it possible for 30 the axle sections 19 and 20 to have independent rotation with relation to each other and the differential sleeve, while the sections will be securely coupled against relative longitudinal movement.

In the operation and use of the present 35 invention, it will be understood that the differential coupling sleeve may be applied to the axles of cars in use at the present time, or to the axles of cars during the 40 course of manufacture. In either event it has been found desirable to suitably cut the grooves 31 in the outer face of the axle 16. After this has been done the axle may be cut in two at the point indicated by the 45 numeral 32 in Fig. 2 of the drawing to form axle sections 19 and 20. It will be understood, however, that the grooves 31 have been machined in a manner to cause them to accommodate the shoulders 29 formed within the differential coupling 50 sleeve 22, and that before the axle is cut in two care is taken to insure that the grooves and shoulders on the axle and within the differential coupling sleeve will be complementary to permit the assembled sleeve to 55 embrace the axle with a free running fit, while preventing longitudinal shifting movement of the sleeve along the axle.

After the axle 16 has been cut in two to 60 form the sections 19 and 20, the ends of the sections are planed smooth and a wear disc 33 agreeing in diameter with the diameter of the axle and in thickness with the cut formed through the axle, is interposed between the contiguous ends of the axle sec-

tions. The two halves of the differential coupling sleeve may then be secured in position with relation to each other and the axle sections by driving the pins 25 through the series of lugs interlocking along opposite sides of the differential sleeve and thereafter securing the taper pins by the use of cotter pins 27, the taper openings tapering in opposite directions if desired.

It will thus be seen that by the construction here disclosed, independent differential movement of the two wheels of a car axle may be free to take place, due to the provision and use of a simple differential coupling structure which is of sufficient strength to maintain the original strength of the axle and to withstand the shock, strain and stresses to which the axle is subjected, said structure being decidedly simple in its construction, the manner of assembling, and inexpensive both as to initial cost and installation.

While I have shown the preferred form of my invention as now known to me, it will be understood that various changes 90 may be made in the combination, construction and arrangement of parts by those skilled in the art without departing from the spirit of the invention as claimed.

Having thus described my invention, 95 what I claim and desire to secure by Letters Patent is—

1. A differential axle for railroad cars, comprising a two-part axle, a wheel fixed on the outer end of each axle part, a two-part 100 sleeve adapted to embrace contiguous ends of the axle sections and to hold them in longitudinal alignment with each other while permitting relatively free rotation of the axle parts within the sleeve, said sleeve 105 parts being formed along opposite halves with complementary interlocking lugs through which progressively tapered openings occur, tapered pins adapted to be driven through the openings in said lugs to 110 rigidly hold the halves of the sleeve in fixed relation to each other and the axle, and means within the sleeve to prevent longitudinal movement of the sleeve on the axle parts.

2. A differential axle for railroad cars, 115 comprising a two-part axle, a wheel fixed on the outer end of each axle part, a two-part sleeve adapted to embrace contiguous ends of the axle sections and to hold them in longitudinal alignment with each other 120 while permitting relatively free rotation of the axle parts within the sleeve, said sleeve parts being formed along opposite halves with complementary interlocking lugs through which progressively tapered openings occur, tapered pins adapted to be 125 driven through the openings in said lugs to exclusively and rigidly hold the halves of the sleeve in fixed relation to each other and the axle, and means within the sleeve to pre- 130

vent longitudinal movement of the sleeve on the axle parts.

3. A differential axle for railroad cars, comprising a two-part axle, a wheel fixed 5 on the outer end of each axle part, a two-part sleeve adapted to embrace contiguous ends of the axle sections to hold them in longitudinal alignment with each other while permitting relative free rotation of 10 the axle parts within the sleeve, said sleeve being formed along opposite edges with complementary interlocking lugs having openings which register when the parts of the sleeve are in their assembled positions, 15 and members passing through the lugs and parallel to the axis of the axles for holding said sleeve parts in fixed relation to each other upon the axles.

4. A differential axle for railroad cars, 20 comprising a two-part axle, a wheel fixed on the outer end of each axle part, the contiguous portions of the axles being formed with a plurality of spaced circumferential grooves on their cylindrical surfaces, a two- 25 part sleeve adapted to embrace the contiguous ends of said axles, said sleeve being formed with shoulders to fit within the circumferential extending grooves on the cylindrical face of the axle parts, a plurality 30 of interlocking lugs formed along opposite complementary edges of the sleeves, said

lugs having registering openings and members extending through said openings and parallel to the axle for rigidly holding the sleeve sections in fixed relation to each other 35 and in their fitted position upon the axle parts.

5. A differential axle for railroad cars, comprising a two-part axle, a wheel fixed on the outer end of each axle part, the contiguous portions of the axles being formed with a plurality of spaced circumferential grooves on their cylindrical surfaces, a two-part sleeve adapted to embrace the contiguous 40 end of said axles, said sleeve being 45 formed with shoulders to fit within the circumferential extending grooves on the cylindrical face of the axle parts, a plurality of interlocking lugs formed along opposite complementary edges of the sleeves, said 50 lugs having registering openings and members extending through said openings and parallel to the axle for rigidly holding the sleeve sections in fixed relation to each other 55 and in their fitted position upon the axle parts, said registering openings in the lugs forming a substantially continuous tapered opening throughout the length of the sleeve and the fastening members passing therethrough being also tapered.

JAMES B. POPE.
